Primary Examiner — Jack Reickel*Assistant Examiner* — Bobby W Jones, II(74) *Attorney, Agent, or Firm* — Greer, Burns & Crain, Ltd.(57) **CLAIM**

The ornamental design for a filter system housing with display, as shown and described.

DESCRIPTION

FIG. 1 is a front view of the filter system housing with display showing the new design;

FIG. 2 is a left side view thereof;

FIG. 3 is a right side view thereof;

FIG. 4 is a rear view thereof;

FIG. 5 is a top view thereof; and,

FIG. 6 is a bottom view thereof.

The broken lines in FIGS. 1-6 represent portions of the filter system housing with display that form no part of the claimed design.

1 Claim, 4 Drawing Sheets(56)
